WASHING MACHINE

Enrique Schele, East Paterson, N.J., assignor to National Rubber Machinery Company, Akron, Ohio, a corporation of Ohio

Application October 4, 1955, Serial No. 538,301

3 Claims. (Cl. 68—4)

The present invention relates generally as indicated to a washing machine, and more particularly to the combination of such washing machine with a food waste disposer.

At the present time, many domestic kitchen sinks are equipped with food waste disposers of the type providing a waste-receiving cavity in communication with the sink drain and having an electric motor driven impeller upon which food waste is supported and comminuted by the action of cooperating shredding elements of the impeller and cavity wall, the comminuted food waste being flushed into the sewer by running water into the sink and through the sink drain opening and disposer.

Accordingly, an ever increasing number of homes thus being equipped with food waste disposers have available a convenient source of power for converting the kitchen sink into the tub of a clothes washing machine. However, because of the limited space and excessive expense, it has not been possible to make such conversion with a washing machine attachment operating on the same principle as the conventional oscillating agitator washing machine.

With the foregoing in mind, it is a principal object of this invention to provide a simple and efficient direct drive washing machine attachment for a food waste disposer which has a unique form of vibratory agitator.

It is another object of this invention to provide a washing machine attachment for a food waste disposer which has a vibratory agitator effective to vibrate the water and clothes therein and to induce an orbital motion to the water and clothes while pulsated or vibrated in generally vertical radial planes so that all of the clothes are effectively and quickly washed and without the clothes contacting the agitator except incidentally as a result of their orbital movement as aforesaid.

Further objects of the present invention, insofar as the combination of the washing machine attachment with a food waste disposer is concerned, are as follows:

A. To provide a control cover which constitutes a bearing for the agitator drive shaft and which is adapted to be locked to the food waste disposer and while thus locked operative to energize the drive motor of the disposer;

B. To provide a novel form of packing ring disposed between the control cover and the sink flange, which packing ring in undeformed condition permits draining of water from the sink without removing the washing attachment, and which, in deformed condition, serves to close the sink drain opening so that water may be retained therein during the washing operation;

C. To provide a combination sealing ring which is not only effective to provide a fluid seal between the agitator and the control cover and drive shaft therewith, but, in addition, to permit vibration of the agitator without rotation of the latter about its central longitudinal axis; and

D. To provide a simple form of vibration producing

2

means which basically includes a shaft with a tilted eccentric to which an agitator is journaled.

Other objects and advantages of the present invention will become apparent as the following description proceeds.

To the accomplishment of the foregoing and related ends, the invention, then, comprises the features herein-after fully described and particularly pointed out in the claims, the following description and the annexed drawing setting forth in detail a certain illustrative embodiment of the invention, this being indicative, however, of but one of the various ways in which the principle of the invention may be employed.

Broadly stated, the washing action obtained with the present washing machine and washing machine attachment is obtained by imparting to a longitudinally finned agitator flared outwardly at one end, a vibratory motion such that the axis of the agitator describes a generally conical path, of which path the apex is adjacent the apex of the flared end of the agitator whereby the water in the sink is caused to move bodily, while vibrated, in orbits disposed in generally vertical and radial planes.

In the annexed drawings:

Figs. 1—5 illustrate the present washing machine-food waste disposer combination; Fig. 1 being a side elevation view; Fig. 2 being a vertical cross-section view taken substantially along the line 2—2, Fig. 4; Fig. 3 being a fragmentary vertical section through the control member; Fig. 4 being a horizontal cross-section view taken substantially along the line 4—4, Fig. 2; and Fig. 5 being a top plan view of the agitator as viewed from the top of Figs. 1 and 2.

Referring now more particularly to the drawings, there is shown therein a portion of a typical kitchen sink 1 which, as will hereinafter appear, constitutes a container or tub for water in which soiled clothes are to be washed, said sink 1 having a center drain opening 2 to which is connected a food waste disposer 3.

Said disposer is herein exemplarily illustrated as comprising a housing 4 forming a waste-receiving cavity 5 within which an impeller 6 is rotated by the drive shaft 7 of an electric motor 8. The wall of the cavity 5 is formed with a cutting element, herein in the form of a shredding ring 9, against which the food waste is impelled by centrifugal force and comminuted by the action of the upstanding fins 10 on the top surface of the impeller 6.

The comminuted waste is flushed out of the cavity 5 through peripheral openings (not shown) around the impeller 6 defined between the cavity wall and the periphery of the impeller by continuous flow of water into the sink drain opening 2 and out into a sewer pipe by way of the discharge pipe 11.

The connection between the sink 1 and the disposer 3 comprises a sink flange 12 engaging the top marginal edge of the drain opening 2 and having a neck projecting downwardly through such opening into threaded engagement with the upper end of the disposer housing 4. A fluid-tight seal with sink 1 is obtained by providing a ring 14 which, when urged upwardly by the plurality of bolts 15, presses the resilient gasket 16 tightly against the bottom of the sink 1 and against the outer surface of the sink flange 12.

The lower end of the sink flange is turned inwardly, as shown, to form a seat 17 adapted to be engaged by a complementary outwardly projecting flange of a control member (not shown herein) which may be substantially identical to that shown in the patent to Drew 2,657,397, granted November 3, 1953.

The disposer control cover, as illustrated and described in detail in said Drew patent has a top continuous flange and a bottom interrupted flange so arranged that, when

said control member is inserted in one rotary position into the sink flange, the same will be supported in elevated "Drain" position by the bottom flange thereof resting upon inwardly extending, diametrically opposed lugs 18 in the disposer housing 4, whereby the top flange will be spaced above the seat 17 so that water may drain from the sink 1. When said control member is inserted in a different rotary position, the interrupted bottom flange will clear the lugs 18 aforesaid whereby the control member will drop down to "Seal" position with its top flange-engaging seat 17, thereby closing the sink drain opening.

The control member is also arranged so that, when it is rotated to "Grind" position while in "Drain" position, a circumferentially extending cam thereof actuates a plunger (not shown) which, in turn, actuates a switch (not shown) for energizing the disposer motor 8. The switch-actuating plunger is not shown herein but will be preferably located just below the lugs 18 as in said Drew patent.

A further feature of the control member for the disposer is that, when it is thus rotated to the motor-energizing position, the lugs 18 will be disposed between spaced-apart flanges of the control member so that the latter cannot be axially withdrawn from the charging opening. In this way, there is no danger that food waste bouncing around in the cavity 5 will accidentally dislodge the control member.

Moreover, the direction of rotation of the impeller 6 and of the food waste is such that the control member is not tended to be rotated to the "Drain" position.

Referring now to the washing machine attachment, the impeller 6 is held on the motor drive shaft 7 as by means of a nut 20 which, as shown herein, constitutes a convenient power take-off for operating the washing attachment, the drive shaft 21 of the washing attachment being provided with a socket 23 at its lower end complementary with said nut 20 so that the washing machine drive shaft will be rotated in unison with the impeller 6 and the motor drive shaft 7 which, for instance, may be 1725 r.p.m. As evident, the disc-like impeller 6 constitutes a fly wheel for the washing machine attachment.

The washing machine drive shaft 21 is rotatably supported in sleeve bearings or bushings contained in the hub of a control member 24, there preferably being a rubber or rubber-like ring disposed between the ends of the bushings to provide a fluid-tight seal around said drive shaft 21 and to maintain pressure between the flange of the bottom bushing and the collar on said shaft.

The control member 24 herein shown somewhat resembles the disposer control member, above referred to, in that it has an interrupted bottom flange 25 which is adapted to be inserted down below the lugs 18 whereupon, when the control member 24 thus inserted is rotated as by means of the pair of diametrically opposed ears 26 on the top thereof, said flange 25 will underlie the lugs 18 and thus the control member is held against upward axial withdrawal. At the same time, said flange 25 will be formed with a circumferentially extending cam to actuate the switch plunger in the manner already described in connection with the disposer control member.

Disposers are usually provided with two switches in series, one being actuated by the control member as aforesaid, and the other being located on the outside of the housing 4 beneath the sink. It may be preferred, when using the present washing machine attachment, to keep the housing switch open until after the control member and other parts have been properly adjusted and secured in place. Thus, when the control member actuated switch is closed by the turning of the control member 24, the disposer motor 8 will not yet be started.

Press fitted or otherwise secured within the bottom

of the skirt of the control member 24 is a ring member 27 which carries a sealing ring 28 as an added precaution against fluid leakage.

Intermediate the ends of the control member 24, there is a continuous ledge or flange 29 which is engaged by the lower end of a flexible sealing ring 30, said ring 30 being of normal shape and size as shown in Fig. 3 so that its outer periphery is spaced from the interior wall of the sink flange 12. Thus, in this position, the sink drain opening is open so that water may drain from the sink 1.

Above said ledge 29, the control member 24 is provided with a plurality of radially projecting pins 31, preferably three in number, and surrounding said control member 24 is a cam ring 32 provided with circumferentially extending cams 34 engaged under said pins 31 so that, when said cam ring 32 is rotated as by means of a wrench engaged with the upstanding pair of lugs 35 thereof, the ring 32 is urged downwardly to deform the sealing ring 30 as shown in Fig. 2 into fluid-tight engagement within the sink flange 12.

A follower ring 36 is preferably interposed between the sealing ring 30 and the cam ring 32 so that the former will not be twisted by the rotation of the latter. With the drain opening of the sink 1 thus closed, the sink 1 may now be filled with water to the desired washing level, and when it is desired to drain out the washing water, all that it is necessary to do is to turn the cam ring 32 back to its initial position, whereupon the sealing ring 30 will return to its undeformed condition as shown in Fig. 3. The ring 30 may be made as of neoprene of 65 to 75 durometer hardness with a wall thickness of $\frac{1}{16}$ " at the center and about $\frac{3}{16}$ " adjacent the rounded ends.

In the form of the invention illustrated in Figs. 1-5, the upper end of the drive shaft 21 is bent as shown and is connected through the ball bearing 37 to the center hub of an agitator 38. The upper end portion of the agitator 38 is flared outwardly and upwardly and is formed with a plurality of axially extending, radial fins 39.

Rotation of the agitator 38 about its central longitudinal axis is prevented by means of the resilient ring 40 which has its opposite ends wedged into wedge grooves formed in the top of the control member 24 and in the bottom end of the agitator hub. Said resilient ring 40 also serves as a fluid seal and is adapted to be flexed as the agitator 38 is vibrated. A ring 40 of 1" O.D., $\frac{11}{16}$ " length, and $\frac{1}{8}$ " wall thickness has well served its intended purposes when made of 50-60 durometer hardness neoprene.

As evident, when the drive shaft 21 rotates, the central axis of the agitator 38 will describe a conical path and will, in effect, rock back and forth in every radial plane between the dot-dash line and solid line positions of Fig. 2. The fins 39 define pockets therebetween, whereby the surrounding water in the sink 1 and the soiled clothes being washed will have imparted thereto a gyroscopic motion as indicated by the arrows and will move around in the sink 1 along this path without any except incidental contact with the agitator, and thus even delicate pieces of clothing may be safely washed without tearing or other severe washing action as is encountered in the conventional oscillating agitator washing machines wherein the clothes are alternately pushed and pulled in opposite directions by agitator fins.

As an example of the present embodiment of the invention, the vibrations will have a frequency of say 1725 cycles per minute, the same as the r.p.m. of the motor 8. In a conventional kitchen sink of 8 x 15 x 21" size, the water level will preferably be about 1" above the agitator to cover the entire agitator 38 which herein is of about 3" overall length flared out at an included angle of approximately 120° from a diameter of $\frac{1}{4}$ "

to a diameter of $3\frac{1}{4}$ ", the radial fins 39 extending to the same diameter and having their lower ends beveled at say an angle of about 45° .

The angle of the bend of the shaft 21 is about 4° so that the vibratory movement as measured at the outer edge of the flared skirt of the agitator 38 is about $\frac{5}{16}$ ". With such construction, it has been found that soiled clothes are thoroughly washed in a matter of 7-10 minutes as compared with a much longer washing cycle and use of much more water in the tub of the conventional oscillating agitator washing machine. Moreover, the washing action herein, besides being efficient, is extremely gentle on the clothes. In addition, the mechanism is extremely simple and does not require any gearing or links, but, instead, is a direct drive unit which results in a vibratory or pulsatory motion of the agitator.

Moreover, the present washing machine attachment makes use of an existing source of power and is especially convenient to use when only a few pieces of clothing are desired to be quickly and efficiently washed.

After the washing has been completed, all that it is necessary to do is to turn the cam ring 32 to drain out the water from the sink and, if desired, clean water may be admitted to rinse the clothes with the same efficient vibratory action. The agitator has a drain opening 41 to drain water from the flared skirt and the bearing 37 is sealed in by cap 42.

It has been found that the vibration induced in the water causes the same to rapidly move back and forth through the clothes to free the dirt therefrom, and this, in combination with the more or less continuous gyrating motion in orbits having generally horizontally disposed axes, effects an efficient washing action never contemplated heretofore by others skilled in the art.

In addition, the washing machine drive is extremely simple, since there is a direct transmission of power from a drive motor to an eccentrically disposed member which causes the agitator to have a vibratory motion, without rotating about its axis in a conical path, the fins of the agitator forming therebetween pockets for gyratory motion of the water and clothes and the imparting of vibration to the water and clothes for the efficient washing action.

In the Figs. 1-5 embodiment of this invention, the agitator 38 is vibrated in the desired manner by a drive mechanism comprising a motor drive shaft 7, and a shaft 21 which is detachably coupled to shaft 7 and which has a bent or offset end to which the agitator 38 is connected by means of a bearing 37.

Other modes of applying the principle of the invention may be employed, change being made as regards the details described, provided the features stated in any of the following claims, or the equivalent of such, be employed.

I therefore particularly point out and distinctly claim as my invention:

1. A washing machine attachment for a food waste disposer of the type which is mounted underneath a kitchen sink to receive food waste from the sink drain opening and which has a motor-driven impeller upon which such waste is supported and impelled for comminution, said attachment comprising a drive shaft adapted for detachable driving engagement with such impeller, a cover member providing a bearing for said shaft and adapted to seal such drain opening, said shaft being provided with a laterally offset portion, an agitator rotatably connected to said offset portion in a tilted position so as to be supported in upwardly projecting relation above the bottom of the sink and to be moved in a generally conical path about an axis which is tilted with respect to the axis of said drive shaft.

of said drive shaft, said cover member having a flexible sealing ring therearound, and means for deforming said ring from drain permitting position to fluid-tight sealing engagement with such drain opening.

5 2. A washing machine attachment for a food waste disposer of the type which is mounted underneath a kitchen sink to receive food waste from the sink drain opening and which has a motor-driven impeller upon which such waste is supported and impelled for comminution, said attachment comprising a drive shaft adapted for detachable driving engagement with such impeller, a cover member providing a bearing for said shaft and adapted to seal such drain opening, said shaft being provided with a laterally offset portion, an agitator rotatably connected to said offset portion in a tilted position so as to be supported in upwardly projecting relation above the bottom of the sink and to be moved in a generally conical path about an axis which is tilted with respect to the axis of said drive shaft, a cam ring rotatable on said cover member and having cam surfaces effective to axially move same relative to said cover member when rotated, and a flexible sealing ring between said cam ring and a flange on said cover member adapted to be radially outwardly deformed in fluid-tight contact with such drain opening upon rotation of said cam ring.

10 3. The combination with a kitchen sink having a drain opening in the bottom thereof of a food waste disposer mounted underneath said sink and provided with an inlet opening to receive food waste through said drain opening, said disposer having a motor-driven impeller upon which such waste is supported and impelled for comminution; and a washing machine attachment in said sink, said attachment comprising a vertical drive shaft having detachable driving engagement at its lower end with said impeller, a cover member providing a bearing for said shaft and sealing said drain opening whereby said sink may be filled with washing fluid, said shaft being provided with a laterally offset portion at its upper end, an agitator rotatably connected to said offset portion in tilted position so as to be supported in upwardly projecting relation above the bottom of the sink and to be moved in a generally conical path about an axis which is tilted with respect to the axis of said drive shaft, and means for axially releasably holding said attachment in place with respect to said sink and disposer, said means comprising radially extending surfaces on said cover member and disposer inlet opening which, in one rotary position of said cover member in said drain opening, are radially overlapped with the surfaces of said cover member underneath those of said inlet opening to preclude upward withdrawal of said cover member and which, in another rotary position of said cover member in said drain opening, are circumferentially offset to permit upward withdrawal of said cover member and disengagement of said shaft from said impeller.
